UNITED STATES PATENT OFFICE.

HARRY D. LILLIBRIDGE, OF ZANESVILLE, OHIO, ASSIGNOR TO AMERICAN ENCAUSTIC
TILING COMPANY, LTD., OF NEW YORK, N. Y., A CORPORATION OF NEW YORK.

HAND-OPERATED TILE-PRESS.

1,238,415.

Specification of Letters Patent. Patented Aug. 28, 1917.

Application filed July 28, 1913. Serial No. 781,502.

To all whom it may concern:

Be it known that I, HARRY D. LILLIBRIDGE, a citizen of the United States, residing at Zanesville, county of Muskingum, and State 5 of Ohio, have invented a certain new and useful Hand-Operated Tile-Press, of which the following is a specification.

This invention is a hand-operated press, the same being especially useful in securing 10 the pressure on clay material required in the manufacture of clay tiles, although the press may be used for other purposes.

Among the objects of the invention are, first, to effect the easy and rapid charging 15 of the die with the clay material, and the removal from the die of the compressed material, all without substantial interference from the upper plunger and other overhead parts of the press; second, to position 20 the hand-operated means for imparting movement to an upper plunger within convenient reach of the workman; third, to secure a double blow by the upper plunger upon the material in the die, the second 25 part of each blow taking place without involving any displacement of the plunger in contact with the material in the die; to relieve the parts of the main table from strain during the operation of compressing 30 the material; and to improve the machine generally so as to minimize the friction and wear, secure a strong and rigid structure, enable dies of various sizes to be used on the one machine, and provide for easy accessibility 35 to the various parts.

One feature of the invention is a die carrying table connected to the press for swinging movement in a horizontal plane, whereby the table and the die thereon may 40 be positioned out of alignment vertically with the upper plunger for the purpose of charging the die with material prior to the compressing operation or the compressed material may be removed from said die. 45 The table swings easily into and out of position, and it is retained by a latch in fixed relation to the path of the upper die.

With said table co-operates a lower plunger intended mainly for ejecting the compressed material from the die. This plunger is movable to different positions by a co-operating adjusting sleeve and nut, and said plunger is raised or lowered by the movement of a lever and operating means, the

same partaking of the swinging movement 55 of the table so as to be at all times in operative relation to the lower plunger. During the compression of the material, this lower plunger is seated upon the solid base part of the press, thus relieving the table 60 and plunger from undue strain.

Another part of the invention is an upper plunger, a screw for imparting movement thereto, and hand-operated means for rotating the screw. Said upper plunger and 65 screw are connected by a slip joint so as to permit a limited relative movement between them, so that the double blow may be given to the material by the upper plunger. The operating means is, preferably, 70 embodied in a cross bar provided with adjustable handles, and this cross bar is attached by an adjustable connection with the screw, whereby the hand-operated means may be adjusted to suit the convenience of 75 the workman.

Other features of the invention and the advantages thereof will appear from the following detailed description.

In the drawings,

Figure 1 is a side elevation of a hand-operated tile press embodying this invention.

Fig. 2 is an elevation looking toward the right in Fig. 1.

Fig. 3 is a plan view showing the parts in position for operation.

Fig. 4 is a vertical section on the line 4-4 of Fig. 1.

Fig. 5 is a horizontal section on the line 90 5-5 of Fig. 1 showing the die carrying table swung to a position out of vertical alignment with the upper plunger.

Fig. 6 is a vertical section through the die carrying table equipped with the ejecting plunger and the operating and adjusting means therefor.

Fig. 7 is a detail plan view illustrating the guide for the upper plunger.

The framework of the press may be of 100 any suitable form, but it is shown in the drawings as consisting of substantial base members A, upright columns A', a foot member A², and an upper cross member A³. The columns A' are bolted solidly to the 105 base members. The upper ends of said columns are externally threaded for the reception of nuts a which operate to clamp

the upper cross member A³ solidly to said columns, whereby the upper cross member is rigidly attached to the columns, although the nuts and threaded end portions enable 5 said upper cross member to be raised or lowered as desired. The foot piece A² is positioned between base members A and is bolted or otherwise solidly fastened thereto. It will be noted that all the parts of the 10 frame are strong in construction and united solidly together, thereby producing a rigid structure. As shown, the transverse foot-piece A² is provided in its upper face with recesses a' a², the recess a² being of less 15 width than the recess a' so as to result in a bearing shoulder a³, the purpose of which will hereinafter appear.

B designates a table adapted to carry or support a die (not shown) wherein the material is deposited so as to be subjected to pressure and result in a "green" tile or other article. The table is of substantial construction in order to withstand the effect of the pressure, and said table is provided 20 with an opening b with which is adapted to register an open bottom portion of the die, or said die may fit into said opening b of the table, whereby the headed portion of a lower ejecting plunger is adapted 25 to work within the die for the purpose of discharging the compressed material therefrom, as will hereinafter more fully appear. The table is formed at one end with a substantial sleeve C, the latter being mounted 30 to 35 for rotative movement on one of the columns A' of the press frame, whereby said table is adapted to be swung outwardly to the full line position of Fig. 5, or the table may occupy the normal operative position 40 shown in dotted lines in Fig. 5, and in full lines in Figs. 1 to 3, inclusive. Said pivotal sleeve C is supported at its lower portion upon a stop collar or other bearing c, and to insure freedom in the movement of 45 the table and the rotative sleeve it is preferred to employ ball or roller bearings. As shown, roller bearings c' are provided intermediate the sleeve and the column, whereas ball bearings c² are positioned in 50 intermediate the lower end of the sleeve and the collar or shoulder c. Obviously, these ball bearings and roller bearings may be of any preferred form. The free end portion of the swinging table is curved at d, see 55 Fig. 5, in order that said table may have the necessary clearance with respect to one column of the press frame, and said free end of the table is formed or provided with a short arm d' terminating in a handle D. Said short arm carries a latch, shown in 60 Fig. 5 as a sliding bolt e positioned for movement within a guide e' and adapted to be operated by a latch lever E. When the table is moved to its operative position the 65 latch bolt is engaged automatically with a

keeper E' attached to one of the columns A', and thus the latch operates to rigidly lock the table in the operative position.

The table is provided with a depending web f joined to the sleeve C, and depending 70 from this table are brackets f', the lower ends of which are fastened in any suitable way to a vertically positioned barrel F, said barrel depending below the table and united rigidly thereto so as to partake of the swinging movement of said table. As shown more 75 particularly in Fig. 6, the barrel is hollow so as to provide a vertical chamber f², the upper part of which is enlarged, thus resulting in a shoulder g intermediate the enlarged and reduced parts of said chamber. The enlarged upper portion of the barrel is 80 interiorly threaded at g', and within said threaded part of the barrel is screwed a plunger adjusting sleeve G, the upper end 85 of which is provided with a hand wheel g², whereby the sleeve may be rotated within the barrel for the purpose of elevating or lowering the ejector plunger H. Said plunger is shown as a cylindrical stem, the lower 90 part of which is reduced in diameter, and the upper part of which stem is provided with a head H', the latter forming an ejecting element and a compressing element 95 adapted to operate within the die to be carried by table B. The upper enlarged part of plunger H is fitted loosely in the adjustable threaded sleeve G, whereas the lower part of said plunger passes downwardly through the chamber f² of the barrel. The 100 plunger is thus supported in the barrel and the sleeve for reciprocating movement therein, although said plunger is adapted to partake of the movement of the barrel with the swinging table when the latter is moved 105 into and out of operative position. For the purpose of imparting reciprocating movement to the plunger and its head H', means are provided for operation by hand, said operating means being mounted on parts connected with the table for the purpose of retaining the plunger operating means in operative relation to the plunger and to the table irrespective of the position which said 110 table may occupy to the press. Said operating means is embodied in a rock shaft I arranged horizontally across the lower part of the press, one end portion of said rock shaft being mounted in a bearing i provided exteriorly on barrel F, whereas the 115 other end portion of said rock shaft is journaled in a bearing i' provided at the lower end of a hanger i² exteriorly to sleeve C, see Fig. 1. The rock shaft is provided at one end with an upstanding hand lever I' adapted to lie alongside of one column A' of the press frame, and secured rigidly to this rock shaft in any suitable way is a gear I², the latter meshing with a rack I³ which is secured rigidly to the lower reduced part 120 125 130

of plunger H. Said rack I³ extends lengthwise of the plunger for a suitable distance, and with the rack meshes the gear of the rock shaft, a part of the barrel F being cut 5 away on one side thereof at i³.

From the foregoing description it is apparent that the barrel is attached to the swinging table to partake of the movement thereof; that the plunger is mounted in the 10 barrel so that it, also, will partake of the movement of the table, although said plunger is capable of an independent reciprocating movement in a vertical direction, and that the operating means for said plunger 15 are mounted on parts connected with the table, whereby said plunger operating means will also partake of the swinging movement of the table. Furthermore, it is evident that the lever I' may be operated 20 at any time for the purpose of raising the plunger within the barrel in order that the head H' of the plunger will be forced upwardly into the die so as to eject the compressed material therefrom, 25 said lever I being operable, also, to lower the plunger and the ejecting element to a normal position.

The lower end of barrel F fits within the recess a' of footpiece A² forming a part of 30 the press frame when the table occupies a normal position below the upper compression plunger, whereas the lower extremity of plunger H is adapted to enter the recess a² of said footpiece A². The recesses a' a² 35 of the footpiece open through one face thereof for the purpose of permitting the barrel and the plunger to enter or leave the recesses according to the direction in which the table B is moved, and in this connection 40 it should be stated that the recessed footpiece and the barrel are so related to each other that when the table, the barrel and the plunger are in their operative positions the lower end of the barrel rests upon the 45 shoulder a³ of said footpiece, whereby the strain of the barrel is taken up by the footpiece during the operation of compressing the material within the die.

The die carrying table is provided with 50 a die plate J, the same being positioned above the table and parallel thereto. This die plate is provided with a central opening j of somewhat larger size than the opening b of the table, and said die plate is 55 secured adjustably to the table by means of screws j', the latter being attached to the table for rotative movement and threaded into sleeves j² which depend from the die plate. The screws may be rotated for 60 the purpose of raising or lowering the die plate relative to the table, and thus the die plate may be brought closer to, or positioned farther away from, the top of the die. This die plate is adapted to support a cer- 65 tain quantity of clay material in a position

close to the die so that the operator may scrape the surplus material into the die in the operation of striking the latter, or some of the material may be removed from the die and deposited upon the die plate. 70

The upper cross member is provided with a central opening k within which is fitted a bushing K, the latter being interiorly screw threaded, as shown in Fig. 4. Said bushing is provided at its lower end with 75 a flange k' fitting against the under face of the cross member A³, and this bushing is retained in a fixed position relative to the cross member A³ by suitable means.

L designates a compression screw which 80 engages with the female thread of bushing K, said screw passing through and working into the bushing, which thus acts as a nut for the screw. The lower part of the compression screw is provided with a smooth 85 member l and with a foot flange l', the diameter of said foot flange being somewhat greater than the diameter of the smooth member l. Said screw is connected operatively with the upper plunger M which is 90 fitted slidably in a crosshead N, the latter being positioned intermediate the die carrying table and the upper cross member of 95 the press frame. Said crosshead is provided at its end portions with collars n which are fitted on the press columns A' and are clamped rigidly thereto, as shown in Fig. 7, for the purpose of retaining the crosshead in a fixed relation to the press frame, the die table, and the plunger M. 100 This crosshead is provided intermediate its ends with an enlarged guide box O, preferably square in shape, as shown in Fig. 7, and within this guide box are wear plates or shoes O' which conform to the exterior 105 shape of the upper plunger and to the internal shape of the guide box. These shoes are composed of steel or other hard material so as to take up the friction and wear on the upper plunger, and said shoes are readily removable from the crosshead and the plunger so that they may be renewed when worn to a substantial extent. 110

Plunger M is substantially square in cross section and fits snugly within the 115 shoes of the guide box on the crosshead, said parts acting to limit the plunger to a vertical movement and in a predetermined path with respect to the die adapted to be carried by table B. The plunger is fitted 120 for sliding movement within the guide box, and the lower part of the plunger is flanged at m to receive the tile die. In the upper part of the plunger is provided a recess m' and to the top of the plunger is secured a 125 cap plate m². The foot flange l' of the compression screw works loosely within the recess m' of the plunger, whereas the cylindrical part l of the screw passes loosely through a central opening provided in the 130

cap plate m^2 , whereby the plunger and the compression screw are loosely connected together by a slip joint which permits a limited relative movement between said plunger and the screw. The screw is adapted to be rotated for the purpose of imparting vertical movement to the plunger, and when the screw is turned in a downward direction the plunger is lowered into the die and 10 in contact with the material therein, whereby a certain amount of pressure is exerted upon the material due to the weight of the plunger. At this time the foot flange of the screw is in contact with the cap plate of 15 said plunger and on the continued rotation of the screw the latter acts upon a wear plate m^3 positioned upon the bottom of recess m' , whereby the continued downward movement of the screw after the plunger is 20 in contact with the material in the die imparts a second blow to the plunger so that the latter is forced by a double blow upon the material in order to compact said material by the operation of the plunger and 25 screw.

The upper part of the screw carries a collar p provided with a head P , the latter being provided with a central stud p^2 , and upon the head rests the operating lever Q , 30 the latter extending crosswise of the press at the upper part thereof. This operating lever is provided with an aperture which receives the central stud p^2 , and said operating lever is adapted to be fastened rigidly 35 to the head of the screw by bolts q , see Fig. 3. It is evident that the bolts q may be removed so as to allow lever Q to be shifted in one direction or the other, for the purpose of bringing the operating lever in a position 40 convenient to the workman, after which the bolts should be replaced so as to rigidly fasten the lever to the screw. The operating lever is provided at its ends with collars r in which are fitted the upper ends of 45 handles R , the latter being slidable in the collars so as to adjust the handles to a height suitable for the workmen, after which the handles should be made fast with the lever by tightening the binding screws r' . 50 It will be noted that the lever extends crosswise of the press, and that the handles are provided at each end of the lever so as to be within convenient reach of the workmen, whereby the lever and the handles are 55 adapted to be adjusted in the manner described so as to suit the convenience of said workmen.

The operating lever is provided near its 60 end portions with upstanding pins S on each of which is fitted one or more weights s adapted to impart momentum to the lever Q when it is forcibly thrust in one direction or the other by the workmen for the purpose of imparting movement at such a speed to 65 the screw L as to exert a forcible blow upon

the plunger M when the latter is in contact with the material in the die.

Means are provided for locking the screw and plunger when the latter is in either a raised or lowered position, whereby the 70 plunger when elevated is precluded from descending by its weight, and when lowered said plunger is retained in contact with the material. Said means consists of a friction block T composed of hard vegetable fiber 75 or other material. This friction block occupies a recess t provided in one side of bushing K , and with said block engages a clamping screw T' , the latter being screwed into a threaded sleeve t' secured in the crosshead 80 of the press frame. After the compression screw L has been turned the required distance to press the plunger upon the material, the clamping screw T' is operated to press the friction block T into engagement with 85 the threads of the compression screw L , whereby the screw and plunger are retained to hold the material under compression for a desired length of time.

The operation is as follows:—With the 90 plunger in a raised position the operator grasps handle D and releases the latch from the keeper, whereupon pressure is applied to the handle to swing the table outwardly to the full line position of Fig. 5, the sleeve C of said table turning freely around column A' . The die on the table is now in position where the operator can easily place the material therein, and if necessary some of the material can be removed from the die plate 95 J and deposited in the die. The die having been charged, the table is swung to its normal position and fastened by the latch, after which the operator grasps one of the handles R and by a quick movement swings the lever 100 Q , the weight s of which imparts momentum to said lever. The screw is thus turned in a direction to lower the plunger M through the guide in the crosshead, and thus bring the flanged end m of said plunger into contact with the material in the die. The weight and downward impulse thus given to the plunger brings it into contact forcibly 105 with the material in the die, and thereafter the continued rotation of the screw L brings the foot flange l' thereof into forcible contact with the wear plate m^3 of said plunger, the result of which is that the plunger acts with a double blow upon the material in the die. If necessary, the lever Q is operated 110 to forcibly depress the screw and plunger in order to secure the requisite pressure upon the material, and then the clamping screw T' is operated in a direction to force the friction block tightly against the compression screw, thereby retaining the plunger in forcible contact with the material. For removing the compressed tile or other work from the machine, the clamping screw 115 T' is released and the lever arm Q is turned 120 to exert a forcible blow upon the plunger. The plunger is then raised by the continued rotation of the screw L until the foot flange l' thereof is in contact with the wear plate m^3 of the plunger, whereupon the 125 clamping screw T' is operated to hold the plunger in contact with the material. For removing the compressed tile or other work from the machine, the clamping screw T' is released and the lever arm Q is turned 130 to exert a forcible blow upon the plunger. The plunger is then raised by the continued rotation of the screw L until the foot flange l' thereof is in contact with the wear plate m^3 of the plunger, whereupon the clamping screw T' is operated to hold the plunger in contact with the material.

in a direction to rotate screw L so as to elevate plunger M, after which clamping screw T is set so as to keep plunger and screw from descending. The latch E is now released and table B is swung outwardly, after which the operator pulls on the lever I' so as to rotate the rock shaft and the gear thereon, whereupon the gear lifts the rack I² and the plunger H so that the member H' of said plunger will pass upwardly through the die for the purpose of ejecting the compressed material therefrom. The operations of depositing material within the die, and of removing the compressed material from said die are performed while the table occupies a position out of alignment vertically with plunger M.

Having thus fully described the invention, what I claim as new, and desire to secure by Letters Patent is:

1. In a press of the class described, the combination with die-supporting means, of a compression plunger, an operating screw therefor, and means for slidably connecting the plunger and the screw to secure a limited movement between the same.

2. In a press of the class described, the combination with die-supporting means, of a compression plunger, an operating screw having a slip joint connection with said plunger, and a manually operated member attached to the screw for imparting rotative movement thereto.

3. In a press of the class described, the combination with die-supporting means, of a compression plunger, an operating screw

having a slip joint connection with said plunger, and a weighted operating member attached to said screw, said operating member having means whereby a quick throw 40 may be given thereto the momentum of which is increased by the weight carried by said member.

4. In a press of the class described, the combination with die-supporting means, of 45 a compression plunger, an operating screw having a slip joint connection with said plunger, an operating member provided with handles and attached to the screw for imparting rotative movement thereto, and 50 means on said member for retaining removable weights in position thereon.

5. In a press of the class described, the combination with a press-frame having an upper crosshead, a second crosshead fixed 55 in the press-frame below said upper crosshead, and die-supporting means, of a compression plunger angular in cross section, a guide box carried by the second crosshead and slidably receiving the angular plunger 60 for limiting the latter to slidable movement, a rotative screw having a swiveled connection with said plunger, and a hand-operated member attached to said screw.

In testimony whereof I have signed my 65 name to this specification in the presence of two subscribing witnesses.

HARRY D. LILLIBRIDGE.
